PILOT WIRE SUPERVISION

Myron A. Bostwick, Budd Lake, and Bert V. Hoard, Millburn, N. J., assignors to Westinghouse Electric & Manufacturing Company, East Pittsburgh, Pa., a corporation of Pennsylvania

Application June 13, 1939, Serial No. 278,845

7 Claims. (Cl. 177—311)

Our invention relates to the supervision of alternating-current pilot wires for the purpose of detecting all kinds of faults therein, as well as protecting the operators against high voltages which may be induced by inductive interference from parallel power-lines. Pilot-wire faults may consist of short-circuits or crossed wires, open circuits, or grounded conductors. The alternating-current pilot wires to which our invention particularly relates are such as are utilized in protecting a transmission-line against faults.

An object of our invention is to provide novel and effective means for giving the complete pilot-wire supervision just described, or any portion thereof, and to provide pilot-fault-detectors which are utilized either to give an alarm or to short-circuit the pilot wires, either one or both.

A further object of our invention is to provide a pilot-wire supervisory system in which a direct-current source is associated with only one end of the pilot wire, and a supervisory relay or relays are provided for detecting over-currents, under-currents, ground-currents, or any one or combination of these features.

A still further object of our invention is to utilize a special double-winding relay in the supervision of pilot wires.

A still further object of our invention is to utilize a plug-mounted supervisory equipment, detachably connected to the insulating transformer at each end of the pilot wire to be supervised.

With the foregoing and other objects in view, our invention consists in the combinations, systems, methods, circuits, and apparatus hereinafter described and claimed, and illustrated in the accompanying drawing, wherein:

Figure 1 is a simplified diagrammatic view of circuits and apparatus illustrating our invention in a form of embodiment in which complete protection is provided against over-currents, under-currents, ground-currents, and induced currents, in the pilot wires, with the electromagnetic relays illustrated in their deenergized positions, features which are unnecessary to an understanding of our invention being omitted for the sake of clearness;

Fig. 2 is a similar view illustrating a modification, and including an illustration of a double-winding supervisory relay which may be utilized in carrying out our invention; and

Fig. 3 is a similar view illustrating a still further modification, including an illustration of a plug-mounted detachable supervisory equipment at each end of the pilot wire.

Our invention is illustrated as being applicable to a circulating-current pilot-wire protective system for a three-phase transmission-line section 4, which is illustrated as terminating in circuit-breakers 5 and 6, having trip-coils 7 and 8 respectively.

Our invention is illustrated as being applied to the supervision of a double-wire pilot wire 10, the two ends of which are connected, through insulating transformers 11 and 12 respectively, to line-current-responsive voltage-producing means or networks, which we have indicated by rectangles marked HCB, at the respective ends of the protected transmission-line section 4, the two networks HCB being energized from two sets of line-current transformers 15 and 16 at the respective ends of the line-section, so that each of the networks HCB receives polyphase line-currents and supplies single-phase voltages to an end of the pilot wire 10. There are a number of networks known for answering our foregoing description of our HCB networks, and our invention is not limited to any particular network, although our invention is particularly designed for use with the network which is described and claimed in an application of E. L. Harder, Serial No. 183,044, filed January 3, 1938, Patent No. 2,183,646, granted December 19, 1939, for Relaying apparatus, assigned to the Westinghouse Electric & Manufacturing Company.

The insulating transformers 11 and 12 are not an essential, but in most practical cases would be utilized, both for the purpose of insulating the terminal equipment from any possible induced voltages which may appear in the pilot wire, and also for the purpose of providing a low-voltage primary winding P and a high-voltage secondary-winding S1 and S2, the latter being split into the two halves S1 and S2 and being connected to the two wires of the pilot wire 10, while the primary winding P is energized from the associated network HCB. As will subsequently be evident, the insulating transformers also provide a convenient and practical means for separating the alternating relaying current and the direct supervisory current which we utilize.

In the particular embodiments of our invention shown in the drawing, the terminal equipment at each end of the pilot wire 10 includes a line-protecting relay 21 and 22 at the respective ends, said relays having operating coils which are connected across the primary winding of the associated insulating transformer 11 or 12, as the case may be, and having make-contacts 23 and 24, respectively, which are utilized to energize the

trip-coils 7 and 8, respectively, of the circuit breakers 5 and 6. While we have thus illustrated a simple over-voltage tripping relay 21 and 22 for responding linearly to the magnitudes of the voltages appearing across the respective primary windings P of the insulating transformers 11 and 12, it is to be distinctly understood that our invention is not limited to this particular sort of tripping relay, and that it may be applied to any known or subsequently invented forms of tripping relays, including those which are illustrated in the aforesaid Harder application.

The illustrated relaying system is a so-called circulating-current system in which currents are normally circulated in the pilot wire 10, under normal fault-free line-conditions, when the current which enters the line 4 at one end is the same as the current which leaves the line 4 at the other end. In this sort of system, the effective impedance of the pilot wire 10 must be small as compared to the effective internal impedances of the voltage-producing networks HCB which apply voltages to the ends of the pilot wire in response to the line-current at the respective ends of the line 4, so that, under the normal fault-free line-operating conditions, the pilot-wire voltage-drop, which appears in the respective primary windings P of the insulating transformers 11 and 12, will be too small to effectively energize the operating coils of the respective tripping relays 21 and 22. Such a system becomes inoperative in the event of crossed wires in the pilot-wire channel, because such crossed wires will prevent the primary winding P from ever having sufficient voltage to operate the tripping relays 21 or 22. An open circuit in the pilot-wire channel of such a system, accompanied by a current-flow above the setting of the relays 21 and 22, will inevitably result in a tripping operation, unless, as will subsequently be described, the open pilot-wire channel can be short-circuited, as by our supervisory means, within a time which is less than the time required for the operation of the respective tripping relays 21 and 22.

It is the particular object of our present invention to provide a supervisory system such as will detect any one of a number of different kinds of faults in the pilot-wire channel, so as to give an alarm that the pilot-wire protective system is no longer operative, and in some instances, to also operate to short-circuit the pilot-wire so that tripping is no longer possible.

In the particular embodiment of our invention shown in Fig. 1, we also provide protection against induced currents in the pilot wires, by adding equipment, at each end of the pilot wire 10, comprising a neutralizing transformer 26, which serves as an equalizing reactor having two windings which are substantially non-inductive to equal currents flowing in opposite directions in the two wires of the pilot-wire channel 10, while imposing considerable impedance to the flow of induced currents, which would be flowing in the same direction in each of the two wires. In order to provide a path to ground, to make possible the flow of a small amount of these induced currents, sufficient to supply the magnetizing current necessary to cause the neutralizing transformer 26 to develop the necessary 70 neutralizing or back-voltage, without providing a low-impedance by-pass or drainage-path for the circulating alternating current in the pilot wires, and without draining or grounding the supervisory direct currents which will subsequently be

described, we also provide small drainage-capacitors 27 and 28, for grounding the inner ends of the split secondary windings S1 and S2 of the two insulating transformers 11 and 12. A somewhat different arrangement of the neutralizing transformer 26 and drainage capacitors 27 and 28 is described and claimed in the patent to C. Le G. Fortescue, No. 1,728,534, granted September 17, 1929, and assigned to the Westinghouse Electric & Manufacturing Company.

In accordance with the form of our invention which is shown in Fig. 1, the inner ends of the split secondary windings S1 and S2 of each of the insulating transformers 11 and 12 are joined by a relatively low-impedance alternating-current circuit including a capacitor 30 which is relatively large, so that its impedance is sufficiently small to keep the total effective pilot-wire impedance small, relative to the internal network-impedance, as previously described. In a practical embodiment of our invention, capacitors 30 of 10 microfarads capacity have been satisfactorily utilized, one at each end of the pilot wire, although we are not limited to any particular capacity.

In the preferred embodiments of our invention, the supervisory equipments at the two ends of the pilot wire 10 are different from each other, although our invention is not altogether limited to this feature, in some of its more generic aspects.

In Fig. 1, the supervisory equipment which is associated with the insulating transformer 11 comprises a direct-current circuit 32 of relatively high impedance, shunting the capacitor 30 which is connected between the two inner ends of the split secondary windings S1 and S2. This direct-current circuit 32 comprises the operating coil of a very sensitive under-voltage direct-current 40 supervisory relay 33, the operating coil of a sensitive over-voltage direct-current supervisory relay 34, and a diagonal of a rectifier-bridge 35, the other diagonal of which is energized from the secondary winding 36 of a transformer 37, 45 the midpoint of the secondary winding 36 being grounded through a high-voltage fuse 38 and the operating coil of a sensitive over-voltage direct-current supervisory relay 39. The under-voltage supervisory relay 33 has a back-contact 41, while the over-voltage supervisory relays 34 and 39 have front-contacts 42 and 43, respectively, and these relays are arranged so that their contacts 41, 42 and 43 are normally open, during normal pilot-wire conditions when there is no fault on the pilot-wire channel. The three relay-contacts 41, 42 and 43 are utilized to energize fault-detector or alarm-circuits, or to perform any other function which can be controlled by the closing of the relay-contacts.

In Fig. 1, the supervisory equipment at the other end of the pilot wire 10 is illustrated as comprising a relatively high-resistance direct-current circuit in the form of a resistor 45 shunting the capacity 30 which is connected between the inner ends of the split secondary windings S1 and S2 of the insulating transformer 12.

As a result of our use of a high resistance 45 in the direct-current circuit at the receiving end of the supervisory circuit, we obtain a definite increase in the direct-current signal when the pilot wire is shorted at said receiving end. Although our invention is obviously not limited to any particular size of the resistor 45, other than that its resistance should preferably be quite large compared to the impedance of the pilot wire, we

mention, by way of illustration, that we have successfully utilized a resistor 45 having a resistance of 8000 ohms, in conjunction with an over-voltage supervisory relay 34 which picks up, and closes its contact 42, at a current of something like 8 or 9 milliamperes, an under-voltage supervisory relay 33 which is normally energized by the normally circulating direct current of something like 6 milliamperes in the pilot wires 10, said under-voltage relay 33 dropping out at from 2 to 5 milliamperes so as to close its back-contact 41, and a pilot-wire ground detector relay 39 which is similar to the over-voltage relay 34. It will thus be seen that there is another reason why the alternating-current impedance of the capacitors 30 should be small, in addition to avoiding the introduction of a high alternating-current impedance in the pilot-wire 10, because the alternating-current voltage-drop across the capacity 30 must be low enough not to come anywhere near operating either one of the direct-current supervisory relays 33 or 34.

In operation, it will readily be observed from the foregoing description, that our supervisory system which is shown in Fig. 1, will give protection against short-circuits or crossed wires in the pilot channel 10, by the picking up of the over-voltage supervisory relay 34, which responds to the increased flow of operating direct current in the pilot wires, under these conditions, said relay being sufficiently sensitive to detect shorts of 2000 ohms or less. In the event of a breakage of the pilot wire 10, resulting in an open-circuit condition in the pilot-channel, the under-voltage supervisory relay 33 drops out and gives an indication by the closure of its back-contact 41. Ground-faults on either one of the pilot wires 10 result in the flow of current through the pilot-ground detector 39, giving an indication by the closure of its front-contact 43.

The high-voltage fuse 38, which is included in the direct-current grounding circuit in Fig. 1, is utilized to guard against the remote possibility of encountering simultaneously a pilot-wire ground-fault and considerable induction from the transmission-line 4, or from some other power-circuit running parallel to the pilot wire 10. Such a coincidence would subject the supervisory relays 33 and 39 or 34 and 39 to excessive ground-currents which might destroy the relays if said currents were permitted to flow for any appreciable time.

We wish it to be understood that the form of embodiment of our invention, which is shown in Fig. 1, is merely illustrative, and that our invention is not confined, in its entirety, to any particular form of embodiment, except with respect to the most detailed claims.

In Fig. 2 we show a modification of our invention in which the means for protecting against high induced voltage takes the form of a gas-filled lightning-arrester tube 46, at each end of the pilot wire 10, said tube being illustrated as a three-electrode discharge-gap device of the type described and claimed in the patent of J. L. McCoy, No. 1,649,035, granted November 15, 1927, and assigned to the Westinghouse Electric & Manufacturing Company. Two of the electrodes 47 and 48 are connected across the capacitor 30, while the third electrode 49 is grounded. These tubes have a breakdown voltage of 500 volts, so that they will effectively protect the equipment against any induced high voltages in the pilot wire 10.

In the form of our invention shown in Fig. 2,

the supervisory equipment which is associated with the insulating transformer 12 is shown as comprising the operating coil of a sensitive under-voltage direct-current supervisory relay 51, which may be utilized either in place of, or in addition to, the high resistance 45 of Fig. 1. We have illustrated the supervisory relay 51, in Fig. 2, as having its operating coil connected in series with a resistance 52 which can be adjusted for the purpose of regulating the normal supervisory current which flows through the pilot-channel 10.

In Fig. 2, the supervisory relay 51 is provided with a back-contact 53 which is utilized to energize the operating coil of an auxiliary relay 54 which operates sluggishly, as by means of a dashpot 55 or other retarding mechanism, to close its make-contacts 56. The make-contacts 56 are connected across the primary winding P 20 of the associated insulating transformer 12, thus thereafter blocking a tripping operation of the pilot-relay 21. On important transmission lines, it is often desirable to block pilot-relay tripping when "through" faults occur on the transmission line, and to rely upon the usual back-up relays (not shown) to clear internal faults. In some cases, however, the blocking of pilot-wire tripping, by means of the short-circuiting contacts 56, may be a disadvantage, as when the supervisory source 37-35 fails.

In Fig. 2, we also show a modification of the supervisory equipment which is utilized at the other end of the pilot wire 10, in association with the insulating transformer 11, the modification 35 consisting in replacing the short-circuit detector 34, the open-circuit detector 33, and the pilot-ground detector 39 with a single polarized relay 61, which is polarized by means of a permanent magnet 62, having north and south poles as indicated by the letters N and S. The polarized supervisory relay 61 has two operating windings 63 and 64 which are disposed on a common intermediate core-member 65. The polarized supervisory relay 61 is provided with a back-contact 66 and a make-contact 67.

The two energizing coils 63 and 64 of the polarized supervisory relay 61 are connected across the capacitor 30 which is associated with the insulating transformer 11, with said operating coils 50 63 and 64 connected in series with each other, with one diagonal of the rectifier-bridge 35 connected between them, the polarity of the coils 63 and 64 being such that, when current is entering at one coil and leaving at the other, as in the normal circulation of direct current in the pilot-circuit 10, the magnetomotive forces of the two coils add together and partially energize the relay 61 to an intermediate position, such that both its back-contacts 66 and its front-contacts 60 67 are open.

The two relay-contacts 66 and 67 are connected in parallel and are utilized to energize the operating coil of an auxiliary relay 74, which operates sluggishly, as by means of a dashpot 75, to close two make-contacts 76 and 77. As in the case of the auxiliary relay 54 at the other end of the supervised pilot-channel 10, the relay-contact 76 is utilized to short-circuit the associated primary winding P, and hence the associated tripping relay 21. The relay-contact 77 may be utilized to energize an alarm-circuit, which, in general, is the primary object of the supervisory circuit.

In the normal operation of the system shown 75 in Fig. 2, the supervisory relays 51 and 61, at the

respective ends of the pilot-channel 10, are both energized so as to assume such a position that their relay-contacts are all open. The relay 51 will drop out, and close its back-contact 53, in response to either a short-circuit or an open-circuit on the pilot-wires 10, but it will not respond to a single ground thereon. At the other end, the supervisory relay 61 will respond by closing its make-contact 67 in the event of either a short-circuit or a ground on the pilot-channel 10, and it will respond by closing its back-contact 66 in response to an open-circuit or break in the pilot-channel 10.

The result of a response of either one of the supervisory relays 51 and 61 is to energize the associated auxiliary relay 54 or 74, as the case may be, thereby short-circuiting the associated primary winding P and short-circuiting the tripping relay 21 or 22 as the case may be. The time-delay means, which is conventionally represented by the dashpots 55 and 75, is for the purpose of ensuring that the tripping relays 21 and 22 will operate faster than the auxiliary relays 74 and 54, in order to make it possible to secure a tripping operation in response to a fault occurring within the length of the protected line-section 4 at the same time when there occurs a light short-circuit or ground on the pilot-channel 10. It is, of course, understood that, when the auxiliary relays 54 and 74 respond by closing their respective contacts 56 and 76, it will be impossible thereafter to effectively energize the tripping relays 21 or 22.

In both of the previously described embodiments of our invention, the supervisory equipments at the respective ends of the pilot-channel 10 may be mounted either in the substation on the switchboard which is attended by a station-attendant, or they may be mounted directly on the insulating transformers 11 or 12 with which they are associated, which would place the supervisory equipment out of the sub-station away from the places to which the station-attendant has ready access. Where the switchboard mounting is utilized, it is usually necessary to provide some means for protecting the station-attendants or operators from induced voltages, as illustrated at 28—27—28 and 46, in Figs. 1 and 2 respectively.

In Fig. 3, we show a form of embodiment of our invention which is adapted for utilizing the principle of a direct mounting of the supervisory equipment on the insulating transformer, and we do this by putting each supervisory terminal-equipment in an insulated box, 81 and 82 respectively, which is insulatedly mounted on the associated insulating transformer 11 or 12, as the case may be, and which is electrically connected to the four terminals of the split secondary windings S1 and S2 by plug-connections 83 and 84, respectively. The plug-connections 83 and 84 insure easy and safe access to the supervisory equipment-boxes 81 and 82 for inspection and test.

In the equipment illustrated in Fig. 3, the low-impedance alternating-current circuit, comprising the capacitor 39, is permanently connected between the inner terminals of the transformer-secondaries S1 and S2 at each end of the pilot wire, these capacitors 39 being preferably placed outside of the supervisory terminal-boxes 81 and 82. At the so-called sending end, the supervisory terminal-box 81 contains a direct-current circuit which is connected in shunt to the capacitor 39, and which includes the operating coil of a

sensitive supervisory direct-current relay 86, a make-contact 87 of the supervisory relay 86, and a diagonal of the rectifier-bridge 35. The other diagonal of the rectifier bridge 35 is energized, in this instance, from a supply-transformer 88 having well-insulated primary and secondary windings 89 and 90, respectively, for confining the high induced pilot-wire voltages to the circuit of the secondary winding 90. The supervisory relay 86 is provided with two back-contacts 91 and 92, the former being utilized to short-circuit the pilot wire 10, and the latter being utilized as an alarm-circuit. The supervisory relay is also provided with an insulating handle 93, extending outside of the box 81, for the purpose of initially actuating the relay 86, by hand, so as to cause the relay to be thereafter held in its actuated position through the circulating direct current which flows through its operating 20 coil and its make-contact 87.

In Fig. 3, the supervisory terminal equipment in the box 82 at the other end of the pilot wire 10 consists of a direct-current circuit in the form of the operating coil of a sensitive under-voltage direct-current supervisory relay 95, having a back-contact 96 which is utilized to short-circuit that end of the pilot wire 10.

In the operation of the system shown in Fig. 3, the supervisory relay 95 responds, by dropping out and closing its back-contact 96, whenever the circulated direct current decreases as a result of either a short-circuit or an open-circuit in the pilot-channel 10, while the other supervisory relay 86, at the other end of the pilot-channel, 35 responds only to open-circuits which result in a decrease in the circulated direct current in the pilot-channel 10, this response of the supervisory relay 86, resulting in short-circuiting the pilot-channel, through the back-contact 91, and energizing an alarm circuit, through the back-contact 92.

In the event of an open-circuit in the pilot-channel 10, if the short-circuiting of the two ends of the pilot channel, as a result of the closure of the relay-contacts 91 and 96, in Fig. 3, is sufficiently fast, in coordination with the operating time of the respective tripping relays 21 and 22, it may be possible, in some instances at least, to prevent the operation of these tripping 50 relays 21 and 22 as a result of the open-circuit condition in the pilot-channel 10, in installations in which the settings of the pilot-relays 21 and 22 are below full-load conditions on the protected transmission line 4. It will be understood that an 55 open-circuit in the pilot-channel would ordinarily cause a faulty tripping operation, by impressing on each of the tripping relays 21 and 22, a voltage corresponding approximately to the entire internally generated voltage in the respective HCB networks, said voltage being normally short-circuited by the pilot wire 10, so that said voltage is normally almost entirely consumed in the internal impedances of the HCB networks.

While we have illustrated our invention in 65 three different forms of embodiment, which are at present preferred by us, we wish these illustrations to be taken in the sense of illustrations, rather than as limitations on our invention, as it will be obvious that many changes 70 may be made, within the skill of the skilled workers, without departing from the essential principles of our invention. We desire, therefore, that the appended claims shall be accorded the broadest construction consistent with their language and the prior art.

We claim as our invention:

1. In combination, a protected alternating-current line-section, a pilot wire between the ends thereof, line-current-responsive voltage-producing means at the respective ends of the pilot wire for circulating alternating current through the pilot wire during normal fault-free line-conditions, a line-protecting relay at each end of the pilot wire, each line-protecting relay having an operating coil in shunt-circuit relation to the pilot wire, a capacitor in series-circuit relation to the pilot wire at each end thereof, the effective impedances of the pilot wire and the capacitors being sufficiently small to produce no operation of the line-protecting relays during normal fault-free line-conditions, a shunting circuit around each capacitor, each shunting circuit having a resistance which is larger than the impedance of the pilot wire, a direct-current source serially included in only one of said shunting circuits, said one of the shunting circuits also including the operating means of a sensitive direct-current supervisory relaying-means, said supervisory relaying-means having pilot-fault-responsive back-contacts which are open during normal pilot-wire conditions and which are closed in response to a predetermined decrease in the direct current flowing in the pilot wire, and means responsive to a closure of said back-contacts for connecting a circuit across that end of the pilot wire.

2. In combination, a protected alternating-current line-section, a pilot wire between the ends thereof, line-current-responsive voltage-producing means at the respective ends of the pilot wire for circulating alternating current through the pilot wire during normal fault-free line-conditions, a line-protecting relay at each end of the pilot wire, each line-protecting relay having an operating coil in shunt-circuit relation to the pilot wire, a capacitor in series-circuit relation to the pilot wire at each end thereof, the effective impedances of the pilot wire and the capacitors being sufficiently small to produce no operation of the line-protecting relays during normal fault-free line-conditions, a shunting circuit around each capacitor, each shunting circuit including the operating coil of a direct-current supervisory relay having pilot-fault-responsive back-contacts which are open during normal pilot-wire conditions and which are closed in response to a predetermined decrease in the direct current flowing in the pilot wire, each shunting circuit having a resistance which is larger than the impedance of the pilot wire, a direct-current source serially included in only one of said shunting circuits, and means responsive to a closure of said back-contacts for connecting a circuit across that end of the pilot wire.

3. In combination, a protected alternating-current line-section, a pilot wire between the ends thereof, line-current-responsive voltage-producing means at the respective ends of the pilot wire for circulating alternating current through the pilot wire during normal fault-free line-conditions, a line-protecting relay at each end of the pilot-wire, each line-protecting relay having an operating coil in shunt-circuit relation to the pilot wire, a capacitor in series-circuit relation to the pilot wire at each end thereof, the effective impedances of the pilot wire and the capacitors being sufficiently small to produce no operation of the line-protecting relays during normal fault-free line-conditions, a shunting circuit around each capacitor, each shunting circuit having a resistance which is larger than the im-

pedance of the pilot wire, a direct-current source serially included in only one of said shunting circuits, said one of the shunting circuits also including the operating means of a sensitive direct-current supervisory relaying-means, said supervisory relaying-means having pilot-fault-responsive front-contacts which are open during normal pilot-wire conditions and which are closed in response to a predetermined increase in the direct current flowing in the pilot wire, and means responsive to a closure of said front-contacts for connecting a circuit across that end of the pilot wire.

4. In combination, a protected alternating-current line-section, a pilot wire between the ends thereof, line-current-responsive voltage-producing means at the respective ends of the pilot wire for circulating alternating current through the pilot wire during normal fault-free line-conditions, a line-protecting relay at each end of the pilot wire, each line-protecting relay having an operating coil in shunt-circuit relation to the pilot wire, a capacitor in series-circuit relation to the pilot wire at each end thereof, the effective impedances of the pilot wire and the capacitors being sufficiently small to produce no operation of the line-protecting relays during normal fault-free line-conditions, and a shunting circuit around each capacitor, each shunting circuit having a resistance which is larger than the impedance of the pilot wire, a direct-current source serially included in only one of said shunting circuits, said one of the shunting circuits also including the operating coil of a sensitive direct-current supervisory relay having pilot-fault-responsive front-contacts which are open during normal pilot-wire conditions and which are closed in response to a predetermined increase in the direct current flowing in the pilot wire, said supervisory relay being slower, in its operation, than said line-protecting relay, and means responsive to a closure of said front-contacts for connecting a circuit across that end of the pilot wire.

5. In combination, a protected alternating-current line-section, a pilot wire between the ends thereof, line-current-responsive voltage-producing means at the respective ends of the pilot wire for circulating alternating current through the pilot wire during normal fault-free line-conditions, a line-protecting relay at each end of the pilot wire, each line-protecting relay having an operating coil in shunt-circuit relation to the pilot wire, a capacitor in series-circuit relation to the pilot wire at each end thereof, the effective impedances of the pilot wire and the capacitors being sufficiently small to produce no operation of the line-protecting relays during normal fault-free line-conditions, and a shunting circuit around each capacitor, each shunting circuit having a resistance which is larger than the impedance of the pilot wire, a direct-current source serially included in only one of said shunting circuits, the other shunting circuit including the operating coil of a sensitive direct-current supervisory relay having pilot-fault-responsive back-contacts which are open during normal pilot-wire conditions and which are closed in response to a predetermined decrease in the direct current flowing in the pilot wire, said supervisory relay being slower, in its operation, than said line-protecting relay, and means responsive to a closure of said back-contacts for connecting a circuit across that end of the pilot wire.

75 6. In combination, a protected alternating-

current line-section, a pilot wire between the ends thereof, line-current-responsive voltage-producing means at the respective ends of the pilot wire, insulating transformers at the respective ends of the pilot wire, each insulating transformer having a primary winding connected across the associated voltage-producing means and a split secondary winding connected across the associated end of the pilot wire, for circulating alternating current through the pilot wire during normal fault-free line-conditions, a line-protecting relay at each end of the pilot wire, each line-protecting relay having an operating coil connected across the primary winding of the associated insulating transformer, a capacitor connected in series between the split portions of said secondary winding at each end of the pilot wire, the effective impedances of the pilot wire and the capacitors being sufficiently small to produce no operation of the line-protecting relays during normal fault-free line-conditions, and a shunting circuit around each capacitor, each shunting circuit having a resistance which is larger than the impedance of the pilot wire, a direct-current source serially included in only one of said shunting circuits, supervisory means associated with at least one of said shunting circuits for detecting at least one kind of pilot-wire fault, and means responsive to a response of said supervisory means for connecting a circuit across that end of the pilot wire.

7. In combination, a protected alternating-

current line-section, a pilot wire between the ends thereof, line-current-responsive voltage-producing means at the respective ends of the pilot wire, insulating transformers at the respective ends of the pilot wire, each insulating transformer having a primary winding connected across the associated voltage-producing means and a split secondary winding connected across the associated end of the pilot wire, for circulating alternating current through the pilot wire during normal fault-free line-conditions, a line-protecting relay at each end of the pilot wire, each line-protecting relay having an operating coil connected across the primary winding of the associated insulating transformer, a capacitor connected in series between the split portions of said secondary winding at each end of the pilot wire, the effective impedances of the pilot wire and the capacitors being sufficiently small to produce no operation of the line-protecting relays during normal fault-free line-conditions, and a shunting circuit around each capacitor, each shunting circuit having a resistance which is larger than the impedance of the pilot wire, a sensitive direct-current supervisory relay having two operating coils on a common magnetic circuit, a direct-current source, and a grounding means, one of said capacitor-shunting circuits comprising said two operating coils with said direct-current source and said grounding means connected between them.
